[57] **ABSTRACT**

A multi-position holder, especially for an I. V. rod is constructed of a base member and a bracket hinged and angularly adjustable relative thereto and a rod holder member angularly adjustable relative to the bracket.

MULTI-POSITION, MULTI-MOUNT I. V. ROD AND HOLDER

BACKGROUND OF THE INVENTION

Generally, hospital beds are provided with a plurality, as for example, six, brackets which permit vertical positioning of I. V. rods, i.e., those rods to which, for example, support containers for intravenous feeding of patients. However, this type of I. V. rod support only permits adjustment in the height of the rod.

THE INVENTION

A multi-position holder assembly especially adapted to hold an I. V. rod is provided which includes a base member and a bracket hinged to the base member for angular adjustment relative to the bracket. Means are provided for angularly adjusting the bracket relative to the base member. A holder for the I. V. rod is connected to the bracket and is angularly adjustable relative thereto. Means are also provided for angularly adjusting a holder relative to said bracket which comprises a pivot pin attached to the holder member and received in a pivot opening in the bracket, and a lug spaced from the pivot pin and receivable in one of a plurality of spaced openings in the bracket. The means for angularly adjusting the bracket comprises a threaded member axially movable to and from the flange or a ratchet and pawl mechanism.

THE DRAWINGS

FIG. 1 is a perspective view of one embodiment of the invention;

FIG. 2 is a side view of the holder of FIG. 1;

FIG. 3 is a plan view of the holder of FIG. 1;

FIG. 4 is a perspective view of another embodiment of the invention;

FIG. 5 is a side view of the holder of FIG. 4; and

FIG. 6 is a plan view of the holder of FIG. 4.

THE PREFERRED EMBODIMENTS

Reference is now made to FIGS. 1 to 3 which illustrate a first embodiment of the invention and in which the holder is designated with the reference character 10. The holder 10 comprises a base member or mounting plate 12 having holes 14 in the corners thereof through which bolts 16 pass to attach the holder 10 to a wall or the like 18. A bracket or body member 20 is hinged relative to the plate 12 by hinge 22 which is connected to the plate 12 and to the member 20. The body member 20 is a cast shape having joined substantially triangularly shaped flat portions 23 and 24 and a web portion 26. The portion 23 defines a reference plane for an I. V. rod 28 attached to and extending from the holder 10.

The I. V. rod 28, has a T-shaped portion 30 with terminal loops 32 for holding containers (not shown) containing medical solutions or the like, and a reduced diameter rear portion 34 having a radially extending locking lug 36. The portion 30 can be angularly adjusted relative to the axis of the rod 28.

The I. V. rod portion 34 is received in a cylindrical holder 38 attached to the body portion 23 by means of a radially extending pivot member 40 received in an opening 42 in the body portion 23 and the web portion 26 of the body member 20 and a radially extending positioning lug 44 received in any one of a plurality of spaced positioning openings 46 formed in the body portion 22. To lock the I. V. rod 28 into the holder 38, the holder is provided with an axial slot 48 with flanking locking slots 50 to receive the locking lug 36. Thus, the end 34 of the I. V. rod is inserted in the holder 38 with the lug 36 in

the slot 48, then axially rotated, either in a clockwise or counterclockwise direction, so that the lug 36 registers with a slot 50. To remove the I. V. rod, the reverse steps are taken.

The angular disposition of the I. V. rod in the reference plane defined by the portion 23 can be selected by lifting upwardly on the holder 38, and moving the lug 44 from one opening 46 to another.

To tilt the I. V. rod from the horizontal, the web portion 26 of the body 20 is provided with an adjusting screw 52 received in a threaded opening 54. A knurled nut 56 positioned on the screw 52 and in a opening 58 in the body member 20 is provided to move the screw 52 to and from the plate 12. By turning the nut 56 to move the screw 52 against the plate, the body member 20 is pivoted around the hinge point of the hinge 22 and the I. V. rod 28 is tilted from the horizontal through any desired angle as required.

Reference is now made to FIGS. 4 to 6 which illustrate a second embodiment of the invention, which is similar to that described except for the general construction of the body member, here identified as 60 and the means for selecting the horizontal tilt of the I. V. rod 28. Otherwise the parts are generally the same and the same reference characters are used to identify the like parts.

The body 60 is constructed of joined or formed metal plates and the tilting means comprises a notched member 62 pivotably connected by means of a bracket 64 and pivot pin 66 to the plate 12. A pawl 68 is connected to the body member, so as to engage the slots 70 in the member 62, and thus determine the tilt angle of the rod 28.

To assist in changing the tilt angle, a latch means 72 is connected to the notch member 62, whereby by lifting upwardly on the latch means 72, the member 62 can be disengaged from the pawl 68.

What is claimed is:

- 35 1. A multi-position holding assembly for holding an I. V. rod comprising:
  - a flat mounting plate to be secured to a vertical wall in parallel relationship;
  - a bracket hinged to said mounting plate and having a flat portion which normally lies in a horizontal reference plane perpendicular to said mounting plate;
  - 40 an elongated ratchet having a plurality of notches, one of its ends being pivotally connected to said mounting plate;
  - a pawl one end of which is secured to said bracket while its other end is free and receivable in the notches of said ratchet,
  - 45 said bracket being angularly adjustable manually to each of a plurality of different discrete positions to tilt said flat portion away from its normal horizontal plane to different selected tilt angles,
  - 50 the free end of said pawl engaging a different notch in said ratchet in each of the discrete positions in order to lock said bracket in the position selected;
  - 55 a manually controllable latch fixed to said ratchet to facilitate pivoting of said ratchet away from said pawl so that said bracket may be moved from its present position to a different position;
  - 60 a cylindrical holder, connected to said bracket, for receiving an I. V. rod;
  - 65 and means for angularly adjusting said holder in a plane parallel to the plane of said flat portion of said bracket and including a pivot pin attached to said holder and received in a pivot opening in said flat portion and also including a positioning lug spaced from said pivot pin and receivable in one of a plurality of spaced openings in said flat portion.
